UNITED STATES PATENT OFFICE

155,121

DESIGN FOR A BROOCH OR SIMILAR ARTICLE

Henry Bogoff, Chicago, Ill., assignor to Spear
Novelty Co., Chicago, Ill., a copartnership

Application April 11, 1949, Serial No. 1,897

Term of patent 7 years

(Cl. D45—19)

To all whom it may concern:

Be it known that I, Henry Bogoff, a citizen of the United States, residing at Chicago, in the county of Cook and State of Illinois, have invented a new, original, and ornamental Design for a Brooch or Similar Article, of which the following is a specification, reference being had to the accompanying drawing, forming a part thereof, in which—

I claim:

The ornamental design for a brooch or similar article, substantially as shown.

HENRY BOGOFF.
